[57] **CLAIM**

I claim the ornamental design for a disk brake rotor, as shown and described.

DESCRIPTION

FIG. 1 is a side view of a disk brake rotor in accordance with the present invention;

FIG. 2 is an edge view of the disk brake rotor;

FIG. 3 is a side view of a second embodiment of the disk brake rotor;

FIG. 4 is a side view of a third embodiment of the disk brake rotor;

FIG. 5 is a side view of a fourth embodiment of the disk brake rotor;

FIG. 6 is a side view of a fifth embodiment of the disk brake rotor; and,

FIG. 7 is a side view of a sixth embodiment of the disk brake rotor.

It is understood that each embodiment has the same thickness and edge configuration as shown in FIG. 2, and the opposite side of each embodiment is a mirror image of the side shown.

The broken lines which define the bounds of the claimed design form no part thereof.

The broken line environmental showing is for illustrative purposes only and forms no part of the claimed design.
